(57) **CLAIM**

The ornamental designs for a container with closure, as shown and described.

DESCRIPTION

FIG. 1 is a top, front right side perspective view of a container with closure illustrating our new design;

FIG. 2 is a bottom, front, left side perspective view thereof;

FIG. 3 is a front elevation view thereof;

FIG. 4 is a left side elevation view thereof;

FIG. 5 is a right side elevation view thereof;

FIG. 6 is a rear elevation view thereof;

FIG. 7 is a top plan view thereof;

FIG. 8 is a bottom plan view thereof;

FIG. 9 is an enlarged detail bottom perspective view of the front of the container with closure;

FIG. 10 is an enlarged detail top perspective view of the front of the container with closure;

FIG. 11 is a partial cross-section view taken along the line 11-11 in FIG. 3; and,

FIG. 12 is a partial cross-section view taken along the line 12-12 in FIG. 3.

The evenly-dashed broken lines in the drawings illustrate the portions of the container with closure that form no part of the claim. The dot-dash-dot broken lines in the drawings define the bounds of the claims and also form no part thereof.
